United States Patent Office

Des. 198,702
Patented July 21, 1964

198,702

CARAFE

David Douglas, Manitowoc, Wis., assignor to East Wisconsin Trustee Company of Manitowoc, Manitowoc, Wis., a corporation of Wisconsin

Filed Nov. 18, 1963, Ser. No. 77,470

Term of patent 14 years

(Cl. D44—21)

FIG. 2

FIG. 1

FIG. 3

FIG. 4

FIG. 5

FIG. 1 is a front elevation view of a carafe showing my new design;

FIG. 2 is a rear elevational view;

FIG. 3 is a side elevational view;

FIG. 4 is a top plan view; and

FIG. 5 is a front elevational view of the stopper seen in FIGS. 2 and 4.

I claim:

The ornamental design for a carafe, substantially as shown.
